UNITED STATES PATENT OFFICE.

CASIMIR von PHILP, OF BETHLEHEM, PENNSYLVANIA.

PRESSING-MACHINE.

1,295,645.

Specification of Letters Patent. Patented Feb. 25, 1919.

Application filed January 27, 1917. Serial No. 144,823.

To all whom it may concern:

Be it known that I, CASIMIR von PHILP, a citizen of the United States, and resident of Bethlehem, Pennsylvania, have invented 5 certain new and useful Improvements in Pressing-Machines, of which the following is a specification.

This invention relates more particularly to a pressing machine in which the material 10 to be pressed is fed in a continuous web by a step by step motion to intermittently acting pressing mechanism, pressing machines of this type being particularly adapted for pressing cloth fabric, although not necessarily limited to such use.

The invention has for an object to provide novel and improved control means whereby alternate action of the web feed mechanism and pressing mechanism is obtained.

Other objects relate to the accurate feeding of the web to the pressing mechanism and the close relative timing of the cloth feed mechanism and pressing mechanism.

For further comprehension of the invention and of the objects and advantages thereof reference will be had to the following description and accompanying drawings in which I have described and illustrated 25 one embodiment of the invention, the novel features of the invention being clearly defined in the appended claims.

Figure 1 of the drawings is a front elevation in general outline of a pressing machine 30 of the type referred to having the invention applied thereto.

Fig. 2 is an enlarged front elevation, partly in section, of the control mechanism.

Fig. 3 is a horizontal section on the line 40 3-3 of Fig. 2 but on a larger scale and showing only the high pressure valve and its operating means.

Fig. 4 is a detail plan view of the control mechanism, the valves not being shown.

Fig. 5 is a horizontal section on the line 45 5-5 of Fig. 2.

Fig. 6 is a detail horizontal section on the line 6-6 of Fig. 2, showing particularly the low pressure valve operating means.

Fig. 7 is a detail horizontal section on the line 7-7 of Fig. 2, showing particularly the valve control cams.

Fig. 8 is a detail plan view of the cloth feed mechanism.

Fig. 9 is a detail elevation showing the 55 main cloth feed roll and related parts.

Fig. 10 is an enlarged detail elevation taken at right angles to Fig. 9 showing the mounting of the presser roll.

Fig. 11 is a diagrammatic view illustrating the run of the cloth through the press.

In the drawings 1 indicates generally the pressing portion proper of a cloth pressing machine, this pressing portion proper being of any well known or approved construction and having a stationary upper press platen 2, a reciprocable lower press platen 3 and an intermediate or floating platen 4, the platens 2 and 3 being guided in their movement by the columns 5 in the usual 60 manner. Detail reference to the construction of these platens is not deemed necessary as the construction and manner of mounting thereof is well known. The lower platen is reciprocated by hydraulic means as usual 70 the novelty in the present construction, in so far as it relates to the pressing mechanism residing in the means for controlling admission of liquid to raise the platen. The valve device, through the operation of which 75 flow of liquid is controlled, is indicated generally at 10 in Fig. 1. The control means is adapted to alternate the action of the valve mechanism with the cloth feed mechanism, to which further detail reference will 80 be made and which is here shown as operated 85 from a horizontal shaft 11.

Mounted in suitable bearings on the front of the press is the drive shaft 12 which extends above and parallel to the shaft 11. 90 The shaft 12 is connected to the shaft 11 by an intermittently operating connection which I have here shown as a gear 13 fixed on the shaft 11 and meshing with a second gear 14 loose upon the drive shaft and 95 adapted to be engaged at certain times by a clutch 15 on the drive shaft to cause gear 14 to rotate with the latter. The means which I have devised and prefer to employ to effect this intermittent engagement comprises a cam 20 fixed upon a vertical cam shaft 21 journaled in a housing 22 fixed to the press in any suitable manner. This shaft has fixed thereon a worm gear 23 which meshes with a worm pinion 24 fixed to one end of the drive shaft 12 whereby shaft 21 is constantly rotated. Engaging with cam 20 is a roller 25 mounted in the

end of an arm 26 which latter is fixed to a hub 27 which is eccentrically mounted in a sleeve 28 journaled in a suitable bearing 29 on the press, this hub having also secured thereto a clutch yoke 30 which engages the clutch 15 in the usual manner as shown at 5 31. The action of the cam 20, acting through arm 26 and yoke 30 is to release the clutch, a spring 32 which encircles the shaft 10 12 normally tending to throw the clutch into engagement with gear 14. Fixed to sleeve 28 is an arm 33 provided with a pin 34 adapted to engage in any one of a series of 15 perforations 35 in an extension 36 of the journal bracket 29. By this means the 20 rotative axis of the clutch yoke 30 may be varied to effect desired adjustment of the clutch to compensate for wear or for other purposes.

As will be apparent the action of the feeding mechanism is controlled from the cam shaft 21 and the action of the pressing mechanism is also preferably controlled from this shaft by a suitable cam device mounted 25 thereon.

To this end a vertical rock shaft 50 is mounted in any suitable bearings on the press with its upper end adjacent the lower end of the cam shaft 21 on which latter are 30 fixed a pair of cams 51 and 52 disposed one above the other and which are adapted to be engaged by a pair of rollers, 53 and 54 respectively mounted in the ends of a bell-crank 55 fixed on the rock shaft, the arms 35 of the bell crank being vertically offset as shown to cause engagement of the rollers each with its respective cam. The lower end of this rock shaft 50 is connected to, and adapted to operate, the valve mechanism. 40 Referring more in detail to this valve mechanism which includes a high pressure valve and a low pressure valve, the high pressure valve comprising a casing 57 having a pair of valve chambers 58 and 59 in which are disposed valves 60 and 61 mounted on stems 62 and 63, valve 60 being the inlet valve and valve 61 the outlet valve. A passage 64 leads from the exterior of the casing to valve chamber 58 and a suitable pipe leads from a 45 source of fluid under pressure to the passage 64.

A passage 66, controlled by the valve 60, leads from the valve chamber 58 and communicates with the valve chamber 59 by 55 means of a transverse passage 65. From the transverse passage 65 an outlet passage 65a leads downwardly to the exterior of the casing to connect with a passage leading into the low pressure valve, as will presently 60 be pointed out. From the valve chamber 59 a passage 67, controlled by valve 61, leads to the exterior of the casing. The passage 67 is the exhaust through which the initial or "high pressure" exhaust takes place and

may be connected with a suitable pipe to conduct the liquid to any desired point. 65

The valve stems 62 and 63 project through the casing at their forward ends into close proximity to a pair of rods 68 and 69 alined with the stems and guided in a fixed bracket 70 70 the opposite ends of such rods being pivotally connected as at 71 and 72 to a pair of connecting rods or bars 73 and 74 which in turn are pivoted to ears 75 and 76 formed on opposite sides of a hub 77 fixed to the 75 rock shaft 50.

The valves 60 and 61 are normally yieldingly retained seated by springs 80 and 81 bearing between the projecting rear ends of the valve stems and a yoke 82 mounted 80 on a rod 83 fixed to the casing 57 this yoke having sufficient angular movement on the rod to balance the pressure on the two stems.

The low pressure and final or quick action 85 exhaust valves are here combined in a single casing 90 secured in any suitable manner to the frame of the press and containing three valve chambers, 91, 92 and 93 in which are mounted valves 94, 95 and 96 respectively, springs 97, 98 and 99 respectively normally 90 tending to seat these valves.

The stem 100 of valve 94 has mounted upon the forward projecting portion thereof a collar 101 held against rearward movement on the stem by nuts 102 threaded on 95 the stem, a coiled spring 103 bearing between this collar and a second collar 104 slidable on the stem. This latter collar is adapted to be engaged by a pair of fingers 105 projecting from a hub 106 fixed to the 100 rock shaft 50. When the rock shaft is oscillated in one direction these fingers will exert a resilient pressure in an opening direction on valve 94.

The valves 95 and 96 are co-axially disposed in opposed relation, valve 96 being provided with a projecting stem 110 to which is pivoted a pair of links 111 whose opposite ends are connected by a slot and pin 110 lost motion connection 112 to an arm 113 fixed to the rock shaft 50.

Leading to the exterior of the casing 90 are a series of passages 114, 115, 116 and 117. Of these, 116 and 117 communicate respectively with the valve chambers 92 and 115 93 while the passage 115 is controlled by valve 94. The valve chambers 91 and 92 are in constant communication through a passage 118 while a passage 119, controlled by each of the valves 95 and 96 connects the 120 valve chambers 92 and 93. Leading from the passage 116 to the pressure or lift chamber of the press is a pipe 120.

Valve 96 is the intake control valve and the passage 117 is connected through a suitable pipe to a source of fluid under low pressure. Valve 94 is the final or "quick action" 125 exhaust valve and the passage 115, which it

controls, may be connected to conduct the exhaust liquid to any desired point. Valve 95 acts as a check valve to automatically shut off back flow through the low pressure system when the high pressure system is working. The passage 114 leads from valve chamber 91 to the exterior of the valve casting and is connected with the outlet 65^a in the high pressure valve, a suitable union 114^a being provided to connect these passages 114 and 65^a to one another.

Referring now more in detail to the cloth feed mechanism, the shaft 11 extends across the face of the press to either side thereof and has fixed upon opposite ends bevel gears 125 and 126 which mesh with similar gears 127 and 128 on the trunnions of cloth feed rollers 129 and 135 suitably supported in side frame plates of which there are a pair on each side of the press, and which depend from fixed arms 141 and 142 projecting on opposite sides of the press, the side frame plates being numbered 143 and 144. Supported in these side frame plates are cloth feed rollers of which there are a series between each pair of plates, and which are driven in a well known manner in unison at equal surface speeds by suitable trains of gears indicated at 145 and 146 in Fig. 8.

In the view shown in Fig. 1 of the drawings the cloth is fed into the press from the right hand side thereof, this side of the press being designated generally as the feeding in side while the opposite or left hand side is designated as the receiving side. In the present instance there are six of these gear driven cloth feed rollers mounted in the side frame plates on each side of the press, those on the right hand side being numbered 129, 130, 131, 132, 133 and 134 and those on the left hand side being numbered 135, 136, 137, 138, 139 and 140.

In the present instance the main cloth gripping means to advance the web comprises a comparatively large drum or roller 150 journaled in standards 151 projecting upwardly from the arms 142 on the receiving side of the press. Mounted in vertically slidable bearings 152 above this roller is a weighted roller 153 which is adapted to rest freely on the drum 150 and is driven therefrom at equal surface speed by the intermeshing gears 154 and 155 suitably fixed to the drum and roller to rotate therewith. The drum is driven at equal surface speed with the series of rollers carried by the side frame plates 144 by means of a sprocket chain 156 looped over a pair of sprocket wheels 157 and 158 one of which is on the drum shaft and the other fixed to a gear 159 meshing with the train of gears 146. Mounted in the standards below and to one side of the drum 150 is an idler roller 160.

In the present instance the roller 153 is

weighted by means of the removable weights 65 161 upon rods 162 fixed to and projecting up from the slidable bearings. To permit of raising the roller from engagement with the drum when desired I have provided a rock shaft 163 mounted at opposite ends in the 70 standards and passing through enlarged openings 164 in the slidable bearings 152, this shaft being provided with a pair of cams 165 adapted to engage the upper walls of the openings 164 when the shaft is rocked in one 75 direction and raise the bearings 152 and with them the roller 153. This shaft is rocked by means of a bell crank 166 fixed to one end thereof and having at the end of one arm a spring pressed pin 167 adapted to engage in 80 either one of a pair of perforations in a plate 168 projecting from the standard, to retain the roller in raised or lowered position.

In addition to the already described cloth feed rollers suitably mounted idler rollers 170 85 and 171 are provided on the feeding in and receiving sides respectively of the press.

In the application of the invention here shown the cloth is adapted to be fed in two separate webs or "runs" the run of the cloth 90 through the press being shown in Fig. 11. The upper run of the cloth, or that passing above the floating platen 4, is indicated generally by the reference character X and the lower run, or that passing below the floating 95 platen, by the reference character Y. The upper run is fed in over certain of the idler rollers 170, then around the feed roller 131, then back and forth in a series of reaches (X¹, X², X³, X⁴, X⁵) around the feed rollers 100 136, 130, 135 and 129 and between the press platens, passing finally under the feed roller 137 to the main driving roller or drum 150 and then out over certain of the idlers 171. The lower run Y is passed around certain of 105 the idler rolls 170 then around feed roll 134 and back and forth in a series of reaches (Y¹, Y², Y³, Y⁴, Y⁵) around the feed rolls 139, 133, 138, 132 and between the press platens, finally passing under the feed roll 140 to 110 the main cloth driving roll and out.

To permit of operation of the cloth feed mechanism independently of the above described control means when desired, I have provided means whereby the shaft 11 may be 115 driven independently of the shaft 12. As here shown the shaft has fixed on the end thereof a pulley 180 driven by a belt 181 from a pulley 182 on a power shaft 183. Fixed to shaft 11 is a pulley 184 connected 120 by a belt 185 with a pulley 186 on shaft 183. These pulleys 182 and 186 are loose upon shaft 183 and may be alternately operatively engaged therewith in a well known manner by a clutch 187 on the shaft.

The operation of my improved control means is as follows: While the press is in operation the drive shaft 12 and cam shaft

21 rotate constantly. The description of the cycle of operations starts at the point when the cloth feeding means has just come to rest and the press platens are about to be operated, in which position all the valves are closed with the straight face presented by the cams 51 and 52 (see Fig. 7) at right angles to a line intersecting the axes of the shafts 21 and 50, the shaft 50 being in neutral position since neither of the rollers 53 or 54 is engaged by its respective cam. This position is the position assumed just before the parts reach the position indicated in Fig. 7, the direction of rotation of the cam shaft 21 being in the direction of the arrow A in Fig. 7. Rotation of the cam shaft will cause the roller 53 to be engaged by the rise 51¹ on cam 51 and swing the rock shaft 50 in the direction of the arrow B in Figs. 5 and 7. 10 This motion of shaft 50 will cause the arm 113 to pull the valve stem 110 and raise valve 96 from its seat and allow the low pressure fluid to flow in through passages 117, lifting valve 95 from its seat, and pass out through 15 116 and pipe 120 to the press and raise the plunger until the cloth is pressed between the platens 3 and 4 and the entablature 2. As the fluid then comes to rest the check-valve 95 will close automatically by the action of spring 98. By this time the shaft 20 50 has been turned by the cam motion to a point where the rod 68 has engaged the stem 62 of valve 60, the cams 51 and 52 and levers 54 and 55 being then in the position shown 25 in Fig. 7. A slight further rotation of the cam 51 causes the stem 62 of valve 60 to be depressed and the latter opened, establishing communication between the high pressure source and the press through passages 64, 66, 30 65 and 65^a of the high pressure valve and passages 114, 118 and 116 of the low pressure valve and pipe 120.

The concentric portion of cam 51, which extends through substantially 180 deg., is 35 now engaging the roller 53 and, in consequence, valves 96 and 60 remain open while the cam shaft 21 makes a half turn farther. The rise 52¹ of cam 52 then engages the roller 54 and swings the rock shaft 50 in the direction indicated by the arrow D in Figs. 3 and 6, the roller 53 riding down the fall 51¹ on the cam 51. The first part of this motion draws rod 68 back, allowing spring 80 to 40 close valve 60. Since the arm 113 is by this 45 movement swung in an opposite direction to that indicated by the arrow B in Fig. 5 the spring 99 forces valve 96 back to its seat. The fingers 105 also compress the spring 103, this pressure being transmitted to the valve 50 stem 100 of the valve 94 by the collar 101 and nuts 102.

The continued movement of the rock shaft 55 in this direction as the roller 54 travels up to the rise 52¹ of cam 52 causes the rod 69 to engage the valve stem 63 of valves 61 and 60

open the latter, permitting the liquid to escape through pipe 120 and passages 116, 118, 114, 65^a, 65 and 67. When the reduction of the pressure is sufficient spring 103 will push the large valve 94 open and the exhaust will 70 be completed rapidly through passage 115, the roller 54 riding on the comparatively short concentric portion of cam 52 during this period. A slight further movement of the cam shaft returns the rock shaft 50 to 75 neutral position.

The press platens 3 and 4 having fallen, the cloth is free to be advanced again, which is accomplished by roller 25 falling into the depression in cam 20 on the upper end of 80 the cam shaft 21, thus permitting spring 32 to move clutch 15 into engagement with gear 14 and rotate the latter and, through gear 13, the shaft 11. Shaft 11 being geared, as previously pointed out, to all the cloth feed 85 rolls the latter will be rotated and the cloth advanced, the rate of speed of the various parts being arranged to cause the cloth to be advanced the proper distance by the time the roller 25 is moved out of the depression 90 in cam 20 and disengages clutch 15, through arms 26 and 30. As soon as the roller 25 moves out of the depression in cam 20 the rise 51¹ in cam 51 is commencing to engage the roller 54 and the operation of the valve 95 mechanism is repeated.

It will be apparent that various changes and modifications might be made in the construction disclosed without departing from the spirit of my invention and the right is 100 reserved to all changes, modification or departures as come within the scope of the appended claims.

I claim:—

1. In a pressing machine, cloth feeding 105 mechanism, pressing mechanism, automatic means for imparting alternate intermittent operation to said cloth feeding mechanism and pressing mechanism, and means whereby said cloth feeding mechanism may be operated for any desired length of time without operation of the pressing mechanism.

2. In a pressing machine, cloth feeding mechanism, pressing mechanism, a shaft adapted to operate the cloth feeding mechanism, a drive shaft in control relation with the said pressing mechanism, a releasable operative connection between the said drive shaft and the shaft for operating the cloth feeding mechanism, a power shaft, a connection between said power shaft and said drive shaft, and a second connection between said power shaft and the shaft for operating the cloth feeding mechanism, said last mentioned connection being inoperative 120 during normal operation of the pressing member.

3. In a pressing machine, hydraulically actuated pressing mechanism, valve mechanism for controlling said pressing mechanism, 130

- an operating shaft for said valve mechanism, a plurality of rolls for feeding a continuous web to said pressing mechanism, an operating shaft for said rolls, a drive shaft, a cam 5 shaft driven by said drive shaft, a cam upon said cam shaft, means upon said valve mechanism operating shaft engaging said cam whereby said valve mechanism is intermittently actuated, a clutch operated connection 10 between said drive shaft and said feed roll operating shafts, a second cam upon the cam shaft and means engaging said cam adapted to intermittently operate the said clutch alternately to the operation of the valve 15 mechanism by the first mentioned cam.
4. In a pressing machine, hydraulically actuated pressing mechanism, valve mechanism for controlling said pressing mechanism, an operating shaft for said valve mechanism, a plurality of rolls for feeding a continuous web to said pressing mechanism, a constantly rotating drive shaft, a constantly rotating cam shaft driven therefrom, a cam 20 upon said cam shaft, a rocker arm upon said valve mechanism operating shaft engaging said cam whereby said valve mechanism is intermittently operated, a clutch operated connection between said drive shaft and said feed roll operating shaft.
- 30 5. In a pressing machine, pressing mechanism, control means therefor, means including a shaft for feeding a continuous web to said pressing mechanism, a drive shaft, a cam shaft operated thereby and in operative relation to said control means, a cam upon said shaft, an arm in engagement with the said cam, a rotatable hub from which said arm projects, a pair of gears connecting the first mentioned shaft and drive shaft, one of 40 said gears being loose upon its shaft and the other fixed, a clutch adapted to put the loose gear in operative engagement with its shaft, and a second arm projecting from the said hub and engaging the said clutch to operate the latter.
6. In a pressing machine, pressing mechanism, control means therefor, means including a shaft for feeding a continuous web to said pressing mechanism, a drive shaft, a cam shaft operated thereby and in operative relation to said control means, a cam upon said shaft, an arm in engagement with the said cam, a rotatable hub from which said arm projects, a pair of gears connecting the 50 first mentioned shaft and drive shaft, one of said gears being loose upon its shaft and the other fixed, a clutch adapted to put the loose gear in operative engagement with its shaft, and a second arm projecting from the said hub and engaging the said clutch to operate the latter and means for adjusting said hub to vary the position of its rotative axis.
7. In a pressing machine, hydraulically actuated pressing mechanism, valve mechanism for controlling said pressing mechanism, including separate pressure and exhaust valves, means for feeding a continuous web to said pressing mechanism, a cam shaft, an operative connection between said cam shaft and web feeding means adapted to cause intermittent operation of the latter, a rock shaft operatively connected to both the pressure and exhaust valve, and a cam and arm connection between said cam shaft and rock shaft whereby the latter is alternately rocked in opposite directions to operate the said valves. 70
8. In a pressing machine, hydraulically actuated pressing mechanism, valve mechanism for controlling said pressing mechanism, including separate pressure and exhaust valves, means for feeding a continuous web to said pressing mechanism by a step by step motion, and means adapted to 75 act alternately with said web feeding means to cause independent operation of said pressure and exhaust valves.
9. In a pressing machine, hydraulically actuated pressing mechanism, valve mechanism for controlling said pressing mechanism, including low pressure and high pressure and exhaust valves, means for feeding a continuous web to said pressing mechanism by a step by step motion, a rock shaft operatively connected to each of said valves, and means for rocking said shaft to operate the said valves in the order of naming alternately with the action of said web feeding means. 80
10. In a pressing machine, hydraulically actuated pressing mechanism, valve mechanism for controlling said pressing mechanism, including low pressure and high pressure and exhaust valves, means for feeding a continuous web to said pressing mechanism, a constantly driven cam shaft, a cam and arm connection between said cam shaft and web feeding means whereby the latter is caused to operate intermittently, 90
- 105 a rock shaft operatively connected to each of said valves, and a cam and arm connection between said cam shaft and rock shaft whereby the latter is rocked to operate the said valves in the order of naming alternately with the action of said web feeding means. 95
11. In a pressing machine, intermittently acting pressing mechanism, means for intermittently feeding a continuous web to said pressing mechanism alternately with the action thereof, said means comprising a series of comparatively small rollers adapted to support the web while the latter is passing through the pressing mechanism, a comparatively large drum, and a presser roller bearing against said drum, and mechanical connections between said small rollers and drum and pressure roller whereby the same 110 are all driven at equal surface speeds. 100
- 115
- 120
- 125
- 130

12. In a pressing machine, intermittently acting pressing mechanism, means for intermittently feeding a continuous web to said pressing mechanism alternately with 5 the action thereof, said means comprising a series of comparatively small rollers adapted to support the web while the latter is passing through the press mechanism, a comparatively large drum, means for

driving said large drum at equal surface 10 speed with the said rollers, and a displaceable presser roller normally bearing against said drum and means for driving said roller from the drum at equal surface speed therewith.

Signed at Bethlehem, Pennsylvania, this 15 fifth day of January, 1917.

CASIMIR VON PHILP.
